CANDLE LAMP

Hugo J. Della Valle, Flushing, N.Y.

Application May 12, 1958, Serial No. 50,848

Term of patent 14 years

(Cl. D48—2)

Fig. 5.

Fig. 1 is a front elevational view of a candle lamp, showing my new design;

Fig. 2 is a top plan view thereof;

Fig. 3 is an exploded view thereof.

Fig. 4 is a horizontal sectional view, taken on the line 4—4 of Fig. 3; and

Fig. 5 is a partial sectional view taken on the line 5—5 of Fig. 2.

I claim:

The ornamental design for a candle lamp, substantially as shown.
